UNITED STATES PATENT OFFICE.

WILLIAM W. MAJOR AND JAMES C. CARPENTER, JR., OF CLIFTON FORGE, VIRGINIA.

TIE NIPPER.

Application filed August 9, 1927. Serial No. 211,750.

This invention relates to a tool especially designed for use in the laying of railway rails, in the construction of a railway track, the primary object of the invention being to provide a tool which may be positioned over a rail and moved to engage a tie to elevate the tie moving the same into close engagement with the rail so that the rail may be readily spiked thereto.

10 An important object of the invention is to provide means which may be swung into engagement with the tie to bite into the tie as the handle of the tool is being operated, thereby to slightly elevate the tie so that the 15 tool may readily move under the tie to accomplish the lifting thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the 25 scope of what is claimed, without departing from the spirit of the invention.

Referring to the drawing:

Figure 1 is an elevational view illustrating the tool in its active position.

30 Figure 2 is a plan view thereof.

Figure 3 is an end elevational view of the tool and

Figure 4 is a side elevational view illustrating the tool in the act of elevating a tie.

35 Referring to the drawing in detail, the tool embodies a bar having a curved lower portion 5 which extends upwardly and has a right angled portion 6 designed to rest on the rail being laid while the tool is in operation 40 in a manner as shown by the drawing.

Forming a continuation of the right angled portion 6 is a depending arm 7 terminating in a forwardly extended horizontal portion 8 which has a tapered forward extremity 9 so that the forwardly extended end portion 8 may be readily slid under the tie to elevate the same, the tie in the present showing being indicated by the numeral 10. In order that the forwardly extended portion 8 may 45 be held against reverse movement while the tie is being lifted, teeth 11 are formed in the

upper edge of the forwardly extended portion 8, which teeth bite into the tie.

Forming an important feature of the invention is the cant hook indicated at 12, 55 which is pivotally connected to the bar at 13, or at a point adjacent to the curved portion 5 of the bar, the forward end of the hook being sharpened as at 14 to bite into the tie under operation. 60

Carried by the hook 12 is a hook 15 which is so constructed that it will contact with the bar when the hook is moved to its inactive position or position as shown by Figure 1 of the drawing. One end of the bar is tapered and provides a handle 16, the handle and lifting portion of the tool being preferably formed integral.

From the foregoing it will be seen that when it is desired to elevate a tie to a position to closely engage the underside of a rail or base thereof, the tool may be positioned on the rail, the forwardly extended portion 8 thereof being directed under the tie, whereupon the operator exerts a downward pressure on the handle 16, causing the forwardly extended portion 8 of the tool to be forced under the tie where it may be held while the rail is being spiked thereto. 70

Should it be found that the tie is spaced too far from the rail, to be engaged by the forwardly extended portion 8 of the tool, the cant hook may be swung forwardly into engagement with the tie, whereupon a downward movement of the handle 16 causes the cant hook to bite into the tie elevating the same to a position, where the forwardly extended portion 8 may slide under the tie. 75

We claim:

1. In a tool of the class described, a bar 90 having a curved end portion, a right angled portion forming a continuation of the curved portion, a jaw forming a continuation of the right angled portion, said jaw embodying a downwardly and forwardly extended portion, said right angled portion adapted to rest on a railway rail, and said forwardly extended portion adapted to engage under a tie when the bar is swung downwardly, to move the tie into engagement with the rail. 95

2. In a tool of the class described, a bar 100 including a handle portion, an upwardly

curved portion at the lower end of the handle portion, a right angled portion forming a continuation of the upwardly curved portion, and a downwardly extended jaw forming a continuation of the right angled portion, said jaw adapted to engage a tie to move the tie into engagement with the rail on which the tool is positioned, and a pivoted cant hook

carried by the handle portion and adapted to cooperate with the jaw in moving the tie. 10

In testimony that we claim the foregoing as our own, we have hereto affixed our signatures.

WILLIAM W. MAJOR.
JAMES C. CARPENTER, JR.
